(74) Attorney, Agent, or Firm — Dunlap Bennett & Ludwig, PLLC

(57) **CLAIM**

The ornamental design for a golf cart enclosure, as shown and described.

DESCRIPTION

FIG. 1 is a top front perspective view of a golf cart enclosure, showing my new design;

FIG. 2 is a front elevation view thereof;

FIG. 3 is a rear elevation view thereof;

FIG. 4 is a right-side elevation view thereof, with a right-side elevation view being a mirror image thereof;

FIG. 5 is a top plan view thereof; and,

FIG. 6 is a bottom plan view thereof.

1 Claim, 4 Drawing Sheets
